UNITED STATES PATENT OFFICE.

WILLIAM J. McCausland, of Philadelphia, Pennsylvania.

PRINTING-TELEGRAPH.

SPECIFICATION forming part of Letters Patent No. 328,500, dated October 20, 1885.

Application filed June 28, 1884. Serial No. 136,238. (No model.)

To all whom it may concern:

Be it known that I, WILLIAM J. McCausland, of the city and county of Philadelphia, and State of Pennsylvania, have invented new 5 and useful Improvements in Printing-Telegraphs, of which the following is a specification.

My invention has reference to printing-telegraph receivers; and it consists in certain 10 improvements upon Letters Patent granted to me June 3, 1884, and numbered 299,664, principally relating to the device for overcoming the dead-centers and the printing mechanism, all of which is fully set forth in 15 the following specification and shown in the accompanying drawings, which form part thereof.

In the drawings, Figure 1 is a sectional elevation of a printing-telegraph receiver embodying my improvements, on line *xx*. Fig. 2 20 is a sectional plan view of same on line *yy*. Fig. 3 is a perspective view of the mechanism for rotating the type-wheel, and Fig. 4 is a plan view of the type-wheel.

25 A is the frame of the machine.

B is the type-wheel shaft, having the double type-wheel C, in which the letters are in one plane and the figures in the other, there being two printing-pads—one to print the letters 30 and another to print the figures. This type-wheel may be formed of two separate wheels, or they may be made integral.

The shaft B is provided with a large spur-wheel, D. This spur-wheel is rotated by a 35 small pinion, E, secured to a shaft, F, working in bearings *f*, and rotated through the agency of a crank, G, connecting-rod *h*, and lever H, pivoted at *H'*, having its movements limited by set-screws *h'*, and one end drawn down by 40 spring J, the tension of which is regulated by thumb-screw K. This lever is vibrated by a rod, L, carrying the armature L', which is arranged to be attracted by the double pair of electro-magnets M M, arranged in separate 45 divisions of the line-wire N, as shown in Fig. 2, the object of which is to increase the attractive power on the armature. The current, after leaving these electro-magnets, reunites, if desired, and passes to ground.

50 In place of using gears D E, sprocket wheels and chains may be used, or other equivalent

connection, whereby, by rotating shaft F, the type-wheel will be made to revolve.

The shaft F is provided with two pallets, F' F'', arranged diagonally opposite and not in 55 the same plane. Working against these pallets are the levers O O, pivoted at O', and having legs O'', to prevent them pressing on the shaft when not in action. These levers are held toward said shaft by spring O''. These 60 pallets and levers prevent the crank G ever stopping on a dead-center, and are arranged separately, so that in running the shaft F rapidly the levers will have ample time in which to regain their normal position before 65 being called upon again to resist the action of a pallet, and then force it around to prevent crank G stopping on a dead-center. When only one lever was used for the two pallets, fast running of the machine caused the lever 70 to pound upon said pallets, as it had not time to regain its normal position before the next pallet came around. This pounding or hammering made the device more or less unreliable on fast running, and it is therefore the 75 object of this part of my invention to overcome the said defect.

The shaft F is also provided with a ratchet-wheel, Q, having two notches or teeth, *q*, diagonally opposite, and upon the face of said 80 ratchet-wheel the pawl P works, the said pawl being pivoted to a post, P', and pressed down upon the ratchet-wheel with a gentle contact by spring P''. These notches or teeth *q* are arranged relatively to the crank G and pallets F' F'', that when they are in their proper 85 position for effective working the pawl catches in the most rearward of the two teeth *q* of one set, and thereby prevents any possibility of the machine running backward. If from 90 any cause the pawl should not catch the said tooth it will always catch the second tooth, and this will also prevent the reversal of the machine from any cause. This device is put upon the machine as a guard against reversal, 95 and when the machine is running perfectly should not be required.

If desired, the pallets and the ratchet may be secured to the pinion E; or, if desired, they might be secured to a separate wheel or shaft 100 gearing with pinion E or spur-wheel D, as indicated in dotted lines.

R is the printing-lever for the letters, and is pivoted at R', and has an armature, R², adapted to be attracted by electro-magnet S. This lever carries the press-pad r, which 5 works up through an aperture in the frame

A, and also the bar t and feeding-finger T, between which the paper strip is fed. T' is a stationary pivoted pawl, which prevents the paper moving backward.

10 V is the paper-reel, V', the paper, and t' a guide through which it passes, it being guided between the type-wheel C and the press-pads r u, and then under the feeding-pawls T T', as shown. If the lever R is raised, the pad r prints, but, the bar t being raised, the paper is caused to pass between the said bar and pawl T, and after being printed and during the descent of the lever R the paper is shoved forward under the pawl T', and so on, insuring a feed of paper at every printing operation.

15 U is another printing-lever, and is used to print the figures, and carries the pad u. It is pivoted in line with lever R, and has an armature, U², adapted to be attracted by the electro-magnet S'.

Pivoted or hinged to the lever R is a bar, Y, having a slot, Y', and, if desired, a leg, Y², and working in said slot is a pin, u', secured 30 to lever U. When the lever R is printing, the bar Y swings idly; but when the lever U is raised to print a figure it first shifts the bar Y, so that the arm Y² is raised to a vertical position, and then raises said lever R with it in further movement; but just before it prints, and before the lever R would print, the arm Y² strikes the frame A and prevents lever R printing, but pad u, being a little in advance, prints. It is necessary in all cases that the 35 lever R be raised, so as to feed the paper or tape, unless a double set of feed-pawls be provided—one set for each lever. The lever U may be pulled back by a spring, u'.

To work these two levers R and U, I may 45 use a single line-wire, W, in circuit with both sets of electro-magnets S and S', but so wound as to have opposite polarities, and using in connection therewith polarized armatures R² U², so that when the positive pole of the battery was put to line the lever R would operate, and when the negative pole is used the lever U would operate. With the construction shown it would be advisable to make the magnet S' somewhat stronger than magnet S.

55 Instead of using opposite polarities to work the press-armatures they may be worked by two separate lines—one for each magnet S S'; or a single line may be used with a double battery, so that lever R would be worked with, say, 60 four cells and lever U with six cells, for as the lever U is the lightest it would rise quick enough to throw the arm Y² over to stop the full ascent of the lever R; but the particular method of operating these levers is of secondary importance.

In operating, every closing of the circuit N causes the pinion E to make a semi-revolu-

tion, and this turns the type-wheel one letter or one figure, and every break in the line allows the spring J to act and turn the pinion 70 to its original position and turn the type-wheel another figure or letter, and so on.

In practice the speed of this machine is more than double that of the printing-telegraph now in general use, and this great speed necessitates the guarding against any derangement, and the devices employed almost render the use of a unison unnecessary.

75 While I prefer the construction shown I do not limit myself thereto, as the details may be modified in various ways without departing from my invention.

Having now described my invention, what I claim as new, and desire to secure by Letters Patent, is—

85

1. In a printing-telegraph, the combination of a type-wheel, gearing to rotate said type-wheel, a crank to rotate said gearing, and independent mechanism to cause said crank to pass each of its dead-centers, consisting of 90 pallets secured upon the crank-shaft, but not in the same plane, and spring-pressure levers or surfaces adapted to force said pallets over the dead-centers, substantially as and for the purpose specified.

95

2. In a printing-telegraph, the combination of a type-wheel, gearing to rotate said type-wheel, a crank to rotate said gearing, and independent mechanism to cause said crank to pass each of its dead-centers, consisting of 100 pallets secured upon the crank-shaft, but not in the same plane, and spring-pressure levers or surfaces adapted to force said pallets over the dead-centers, and an electro-magnet and connecting devices to rotate said crank, substantially as and for the purpose specified.

105

3. In a printing-telegraph, the combination of a type-wheel, gearing to rotate said type-wheel, a crank to rotate said gearing, and independent mechanism to cause said crank to pass each of its dead-centers, and a stop or catch to prevent the said crank rotating in the wrong direction, substantially as and for the purpose specified.

110

4. In a printing-telegraph, the combination of a type-wheel, gearing to rotate said type-wheel, a crank to rotate said gearing, and independent mechanism to cause said crank to pass each of its dead-centers, a ratchet-wheel having four teeth arranged in pairs, and a pawl to engage with said teeth, to prevent the said crank rotating in the wrong direction, substantially as and for the purpose specified.

115

5. In a printing-telegraph, a type-wheel in which the letters and figures are arranged side by side, gearing to rotate said type-wheel, a crank to rotate said gearing, an electro-magnet and connecting mechanism, substantially as set forth, whereby the crank can assume only two positions, one produced by the electro-magnet when magnetized and the other when it is demagnetized, each of said movements bringing into printing position one letter and one figure, whereby a simple make

120

125

130

and break of the type-wheel-magnet circuit causes a full revolution of the crank and moves two letters and two figures into printing position, substantially as and for the purpose specified.

6. The combination of type-wheel C, shaft F, having crank G and pallets F' F'', levers O, rod or link h, mechanism controlled by the electrical pulsations in the line-circuit to vibrate said rod, and gearing or its equivalent connecting the said shaft F with the type-wheel, substantially as and for the purpose specified.

7. The combination of type-wheel C, shaft F, having crank G and pallets F' F'', levers O, pivoted at O', and having legs O'', springs O', rod or link h, mechanism controlled by the electrical pulsations in the line-circuit to vibrate said rod, and gearing or its equivalent connecting the said shaft F with type-wheel, substantially as and for the purpose specified.

8. The combination of type-wheel C, shaft F, having crank G and pallets F' F'', ratchet-wheel Q, spring-pawl P, levers O, rod or link h, mechanism controlled by the electrical pulsations in the line-circuit to vibrate said rod, and gearing or its equivalent connecting the said shaft F with the type-wheel, substantially as and for the purpose specified.

9. The combination of type-wheel C, spur-wheel D, pinion E, shaft F, having crank G and pallets F' F'', spring-levers O, link h, lever H, spring J, rod L, having armature L', and electro-magnet M, substantially as and for the purpose specified.

10. The combination of type-wheel C, spur-wheel D, pinion E, shaft F, having crank G, mechanism, substantially as set forth, to prevent the shaft F rotating in the wrong direction, and pallets F' F'', spring-levers O, link h, lever H, spring J, rod L', having armature L, and electro-magnet M, substantially as and for the purpose specified.

11. The combination of type-wheel C with levers R and U and connecting mechanism, substantially as set forth, consisting, essentially, of a bell-crank pivoted to one lever, and a pin actuating said bell-crank on the other lever, and a stop in the path of the free arm of said bell-crank, whereby lever R may move independently of lever U, but lever U cannot move without raising lever R also, substantially as and for the purpose specified.

12. The combination of type-wheel C with levers R and U and connecting mechanism, substantially as set forth, consisting, essentially, of a bell-crank pivoted to one lever, and a pin actuating said bell-crank on the other lever, and a stop in the path of the free arm of said bell-crank, whereby lever R may move

independently of lever U, but lever U cannot move without raising lever R also, and a stop actuated by lever U, to limit the movement of lever R when raised by lever U, substantially as and for the purpose specified.

13. The combination of type-wheel C with levers R and U and connecting mechanism, substantially as set forth, consisting, essentially, of a bell-crank pivoted to one lever, and a pin actuating said bell-crank on the other lever, and a stop in the path of the free arm of said bell-crank, whereby lever R may move independently of lever U, but lever U cannot move without raising lever R also, and separate electro-magnets to operate each of said printing-levers, substantially as and for the purpose specified.

14. The combination of type-wheel C with levers R and U and connecting mechanism, substantially as set forth, consisting, essentially, of a bell-crank pivoted to one lever, and a pin actuating said bell-crank on the other lever, and a stop in the path of the free arm of said bell-crank, whereby lever R may move independently of lever U, but lever U cannot move without raising lever R also, and feeding mechanism for the tape actuated by lever R, substantially as and for the purpose specified.

15. The combination of type-wheel C with levers R and U and connecting mechanism, substantially as set forth, consisting, essentially, of a bell-crank pivoted to one lever, and a pin actuating said bell-crank on the other lever, and a stop in the path of the free arm of said bell-crank, whereby lever R may move independently of lever U, but lever U cannot move without raising lever R also, and pivoted bar Y, pivoted to lever R, and having arm Y'', and a sliding connection with lever U, substantially as and for the purpose specified.

16. The combination of type-wheel C with levers R and U and connecting mechanism, substantially as set forth, consisting, essentially, of a bell-crank pivoted to one lever, and a pin actuating said bell-crank on the other lever, and a stop in the path of the free arm of said bell-crank, whereby lever R may move independently of lever U, but lever U cannot move without raising lever R also, and separate electro-magnets to operate each of said printing-levers, a line-circuit, and means to reverse the polarity in said line, substantially as and for the purpose specified.

In testimony of which invention I hereunto set my hand.

WILLIAM J. McCausland.
